DART FOOTBALL GAME BOARD

Charles A. Stitzer, 108 S. Main St.,
Pleasant Gap, Pa. 16823

Filed Jan. 25, 1972, Ser. No. 220,728

Term of patent 14 years

Int. Cl. D21—01

U.S. Cl. D34—5 FG

FIG. 1

FIG. 1 is a plan view of a dart football game board showing my new design; and

FIG. 2 is an edge view taken from the top of FIG. 1.

I claim:

The ornamental design for a dart football game board, substantially as shown.
